CLAIM

The ornamental design for a mixer, as shown and described.

DESCRIPTION

FIG. 1 is a perspective view of a mixer showing my new design,

FIG. 2 is a front view thereof,

FIG. 3 is a rear view thereof,

FIG. 4 is a left side view thereof,

FIG. 5 is a right side view thereof,

FIG. 6 is a top plan view thereof,

FIG. 7 is a bottom plan view, and,

FIG. 8 illustrates an exploded state of my new design.

1 Claim, 8 Drawing Sheets

FIG. 1

FIG. 2

FIG. 3

FIG. 4

FIG. 5

FIG. 6

FIG. 7

FIG. 8
